UNITED STATES PATENT OFFICE.

SEPTIMUS J. RAWSON, OF PHOENICIA, NEW YORK.

DESIGN FOR A HOE.

41,595.

Specification for Design.

Patented July 18, 1911.

Application filed July 15, 1910. Serial No. 572,222. Term of patent 14 years.

To all whom it may concern:

Be it known that I, SEPTIMUS J. RAWSON, a citizen of the United States, residing at Phoenicia, in the county of Ulster and State of New York, have invented a new, original, and ornamental Design for Hoes, of which the following is a specification, reference being had to the accompanying drawing, forming part thereof.

The figure is a perspective view of the hoe, showing my new design.

I claim:

The ornamental design for a hoe, as shown.

SEPTIMUS J. RAWSON.

Witnesses:

JAMES H. BROMLEY,
MARGARET RAWSON.
